US00D905489S

(12) **United States Design Patent** (10) **Patent No.:** **US D905,489 S**
Zhu (45) **Date of Patent:** **** Dec. 22, 2020**

(54) **BACKREST**

(71) Applicant: **Shenzhen MiniCute Technology Co., Ltd.**, Shenzhen (CN)

(72) Inventor: **Wenbin Zhu**, Shenzhen (CN)

(73) Assignee: **Shenzhen Minicute Technology Co., Ltd.**, Shenzhen (CN)

(**) Term: **15 Years**

(21) Appl. No.: **29/682,141**

(22) Filed: **Mar. 1, 2019**

(30) **Foreign Application Priority Data**

Aug. 24, 2018 (CN) 2018 3 0474058
(51) **LOC (12) Cl.** **06-01**
(52) **U.S. Cl.**
USPC **D6/716.4**
(58) **Field of Classification Search**
USPC D6/334-336, 364, 365, 366, 367, 374,

(57) **CLAIM**

The design for backrest, as shown and described.

DESCRIPTION

FIG. 1 is a front view of backrest showing my new design;
FIG. 2 is a rear view thereof;
FIG. 3 is a left side view thereof;
FIG. 4 is a right side view thereof;
FIG. 5 is a top view thereof;
FIG. 6 is a bottom view thereof; and,
FIG. 7 is a perspective view thereof,
FIG. 8 is a top view in a used condition thereof; and,
FIG. 9 is a bottom view in a used condition thereof.
